UNITED STATES PATENT OFFICE

2,088,343

APPARATUS FOR PLAYING GOLF

Bertram Vernon Radley, Teignmouth, England

Application November 25, 1935, Serial No. 51,450
In Great Britain November 26, 1934

5 Claims. (Cl. 273—77)

This invention relates to apparatus for practicing golf swings without a ball and making practice swings with a ball.

Whatever the length of the swing may be, the object to be attained is to make the swing in such a manner that the club head is moving at its highest velocity at the moment of impact, this maximum velocity being obtained by a rapid increase of speed as the ball is being approached, 10 this acceleration being produced by the action of the device and not by the conscious effort on the part of the player. Also that a swing shall be a good one there must be no decrease in the velocity attained at impact till the club head has 15 passed the place, where the ball lay, by some distance.

Now in accordance with this invention this object is achieved by providing a weight device adapted to be connected with the shaft of a golf club, so that it will slide up and down thereon freely during a stroke, the device being composed of divided plungers attached to each other by rubber springs and sliding up the shaft towards the hands during the upswing and sliding down 25 towards the club head as it is approaching impact and finally sliding towards the hands towards the end of that swing.

The accompanying drawing illustrates one form of device made in accordance with this invention.

Fig. 1 is a plan.

Fig. 2 is a front elevation.

Fig. 3 is a section on line 3—3, Fig. 1.

Fig. 4 is a section on line 4—4, Fig. 2, with securing band removed.

Fig. 5 is a side elevation with the cover removed.

Fig. 6 is an elevation of one half of a sleeve plunger.

In the device illustrated I provide a square device comprising two similar sleeve plungers *a*, *a* of square cross-section connected by two or more rubber rings *b*, *b*. Each plunger is divided longitudinally into halves *a'*, *a''*, is flanged at *c'*, *c''* at both ends to form heads and is longitudinally orificed by a hole *d* adapted loosely to accommodate the shaft of a golf club, the hole being square.

The halves *a'*, *a''* are provided with pins *e*, *e* and sockets *f*, *f* whereby they may be accurately adjusted and secured together. The pins *e*, *e* require to be fairly long to prevent the halves *a'*, *a''* of the plungers coming apart. They are also connected longitudinally by rubber rings *b*, *b* of square cross section disposed contiguous to the

flanges *c'*, *c''* at opposite sides of the axial orifices of the sleeves and with their axes at right angles to the said sleeve-axes. The rings are suitably connected to the flanges. In a modified form in place of the rings I may employ two helical springs disposed at diametrically opposite points around the said flanges and attached at opposite ends to opposite flanges. In order to limit the longitudinal relative motion of the plunger, I provide flanged members *g'*, *g''* adapted to fit over the sleeve portions *a*, *a* of the plungers and abut against their adjacent flanges *c'*, thus forming a square casing. A medial elastic band *h* with a fastener *i* is provided to hold the halves together. In order that the halves shall register properly, projections *k'* on member *g'* engage with slots *k''* in member *g''* and projections *m'* and with projections *m''* on member *g''*.

The sides of the square formed by the flanges *c'*, *c''* of the plunger heads should come quite close to the casing formed by the members *g'*, *g''* so that the plungers will be guided by the walls of the casing.

Two stops are provided, one near the bottom of the shaft and the other near the grip, to limit the downward and upward travel of the device on the club shaft. The upper stop will be placed lower down the shaft for practicing short swings than will be the case for long ones.

The lower stop will be placed at such a distance from the bottom of the head of the club that, when the device is in its lowest position, its centre of gravity shall be approximately in the same place as the centre of balance of the club.

In use only the flanges inside the casing need be square. The halves *a'*, *a''* of the plungers are placed in position around the shaft, fitted together by their pins *e*, *e*, and sockets *f*, *f* and the halves *g'*, *g''* of the casing are secured home into the plungers by the projections *k'*, and slots *k''* and projection *m'* and hook *m''*, the casing being finally secured together by the elastic band *h*.

In use the device will slide up and down the shaft being nearest the handle at the top of the swing and nearest the club head at the bottom, and is stopped at the upper and lower limits of travel by the stops.

It will be evident that the details of the invention may be varied in many ways without departing from the scope thereof.

What I claim and desire to secure by Letters Patent is:

1. A weight device adapted to be connected with the shaft of any ordinary golf club without structural alteration of said club, so that it will

slide up and down thereon freely during a stroke, the device being composed of divided plungers attached to each other by at least one rubber spring device and sliding up the shaft towards the hands during the upswing and sliding down towards the club head as it is approaching impact and finally sliding towards the hands towards the end of that swing.

2. A weight device according to claim 1 composed of plungers which are bisected and when assembled form a square orifice for the club shaft.

3. A weight device according to claim 1 composed of plungers which are bisected and when assembled form a square orifice for the club

shaft, wherein the plungers are flanged and are connected together by a casing.

4. A weight device according to claim 1 composed of plungers which are bisected and when assembled form a square orifice for the club shaft, wherein the plungers are flanged and are connected together by a casing, and wherein the plungers are composed of halves that are provided with pins and sockets for registering purposes.

5. A weight device according to claim 1 where in the plungers are attached to each other by annular rubber springs.

BERTRAM VERNON RADLEY.
